UNITED STATES PATENT OFFICE.

EDWARD W. RAWDON, OF AKRON, OHIO.

LOCOMOTIVE DRIVING BOX.

Application filed October 6, 1922. Serial No. 592,755.

To all whom it may concern:

Be it known that I, EDWARD W. RAWDON, a citizen of the United States, residing at Akron, in the county of Summit and State 5 of Ohio, have invented certain new and useful Improvements in Locomotive Driving Boxes, of which the following is a specification.

This invention relates to an improved 10 driving box for locomotives, being similar to the construction shown in my pending application for driving box, Serial No. 576,358, filed July 20, 1922, and seeks, as one of its principal objects, to provide a driving 15 box wherein the box wedge will be automatically adjusted for taking up undue forward and rear play of the box.

The invention has, as a further object, to provide an adjusting mechanism for the box 20 wedge which will be adapted to effectively accommodate vertical movement of the box as well as lateral movement thereof so that said mechanism may properly function regardless of uneven track conditions.

25 And the invention has, as a still further object, to provide an adjusting mechanism employing a ratchet and a plurality of co-acting pawls for adjusting the box wedge, wherein said pawls will be spring pressed 30 into engagement with the ratchet so that said pawls will normally lock the ratchet against retrograde movement, and wherein a connection between the box and said pawls will be provided, of such nature, that when 35 the box shifts forwardly, a straight horizontal pull will be exerted on the pawls, regardless of the vertical or lateral displacement of the box.

In the accompanying drawings:

40 Figure 1 is a fragmentary elevation showing my improved driving box in conjunction with a conventional pedestal;

45 Fig. 2 is an enlarged fragmentary vertical sectional view showing the adjusting mechanism for the box wedge in elevation;

Fig. 3 is a horizontal sectional view on the line 3—3 of Fig. 2, looking in the direction of the arrows;

50 Fig. 4 is a horizontal sectional view on the line 4—4 of Fig. 2, looking in the direction of the arrows;

Fig. 5 is a detail section on the line 5—5 of Fig. 3, looking in the direction of the arrows;

55 Fig. 6 is a detail section on the line 6—6

of Fig. 5, looking in the direction of the arrows, and

Fig. 7 is a fragmentary vertical sectional view showing a slight modification of the invention.

Referring now more particularly to the drawings, I employ a box body 10 in connection with which is illustrated a conventional pedestal 11 having the usual pedestal brace 12. The box body may be of any preferred construction and is provided with the customary flanges to accommodate a shoe 13 and wedge 14 cooperating with the legs of the pedestal. Journaled through the box body is a drive axle, as conventionally illustrated at 15.

Formed in the wedge 14 at its lower end is a recess 16 and threaded through the pedestal brace 12 is a wedge bolt 17 provided at its upper end with a circular head 18 rotatably engaged in said recess. The wedge bolt is provided with oppositely disposed longitudinal grooves 19 and loosely mounted on the bolt to rest upon the pedestal brace 12 is a ratchet 20 having oppositely disposed ribs or feathers 21 slidably fitting in said grooves coupling the ratchet with the bolt. Thus, the ratchet may be turned for rotating the wedge bolt when said bolt will shift endwise through the ratchet. Formed on the ratchet at its lower end is an annular base flange 22 and bolted or otherwise secured to the pedestal brace to overhang said flange are angle brackets 23 rotatably connecting the ratchet with said brace.

Mounted upon the pedestal brace 12 adjacent the ratchet 20 is a pawl housing 25 cut away at one side, as particularly shown in Fig. 3, to accommodate the ratchet. The housing 25 is arranged to extend longitudinally of the pedestal brace and is formed of companion sections on which are formed lugs 26 through which are engaged cap bolts or other suitable fastenings 27 holding the housing sections against separation as well as connecting the housing to the pedestal brace. Formed on the sections at their forward ends are mating ears 28 through which is engaged a bolt 29 connecting the sections of the housing with each other. Freely slidable within the housing is a block 30 provided at its rear end with spaced ears 31 and pivoted between said ears is a plurality of pawls 32. Extending through said ears and through the pawls is

a bolt 33 connecting the pawls with the block and, as will be observed, the top and bottom walls of the housing are provided with slots 34 accommodating the ends of said bolt. 5 The pawls 32 are of graduated length, being disposed to cooperate at their free ends with the ratchet 20, and secured to the outer edges of said pawls near their free ends are springs 35 which extend forwardly toward 10 the block 30 and bear at their free ends against the outer side wall of the housing, holding the pawls in engagement with the ratchet. 15 Bolted or otherwise secured at its ends to the rear leg of the box body 10 is a depending yoke 36 straddling the forward end of the pawl housing 25 and formed in the sides of said yoke are vertical slots 37. The side walls of said housing are provided with 20 similar slots 38 and slidably fitting through the block 30 to extend through said slots is a squared cross rod 39 upon the ends of which are threaded nuts 40 securing the rod against endwise displacement, suitable 25 washers being preferably interposed between said nuts and the sides of the yoke. Thus, the box body 10 may shift vertically when the slots 37 will accommodate the vertical movement of the yoke 36 while, when 30 the box body shifts laterally, said rod will slide through the block 30. It will therefore be seen that regardless of the position of the box body due to local vertical and lateral movement thereof, the yoke 36 will, when 35 the box body shifts forwardly, exert a straight longitudinal pull upon the block 30. Accordingly, as soon as any undue forward and rear play of the box body develops through wear, the block will be shifted longitudinally within the housing 25 when the 40 pawls 32 will coact with the ratchet 20 for rotating said ratchet and turning the wedge bolt 17 to adjust the wedge 14 for taking up such play. At no time will the box body 45 be permitted to pound within the pedestal since adjustment of the wedge will be accomplished automatically and, of course, the pawls 32 will, by being held in engagement with the ratchet by the springs 35, serve to 50 lock the ratchet against retrograde movement and thus maintain the wedge in adjusted position.

In Fig. 7 of the drawings, I have illustrated a slight modification of the invention 55 wherein a wedge is shown at 41, the rear leg of a pedestal at 42 and a pedestal brace at 43. In adapting the wedge to the present improvements I form therein a vertical bore 44 near the lower end of which is a recess 45 and removably seated in said recess is a nut 46. Threaded through the pedestal brace and through said nut is a wedge bolt 47 adapted to be freely received in the bore 44. The wedge bolt is provided with right 60 and left threads engaging similar threads in

the pedestal brace and nut respectively so that, when said bolt is rotated, the bolt will not only rise through the pedestal brace but also the nut 46 will be shifted upwardly upon the bolt for elevating the wedge. 70 Otherwise, this modification is identical with the preferred construction and further description is accordingly believed unnecessary.

Having thus described the invention, what 75 is claimed as new is:

1. In a journal box, a box body, a pedestal operatively supporting the box body, means interposed between the box body and the pedestal adjustable for taking up forward 80 and rear play of the box body, means for adjusting said first-mentioned means including a pawl and ratchet, and an operative connection between the box body and said pawl adapted to accommodate vertical movement of the box body with respect to the pawl.

2. In a journal box, a box body, a pedestal operatively supporting the box body, means interposed between the box body and the pedestal adjustable for taking up forward 90 and rear play of the box body, means for adjusting said first-mentioned means including a pawl and ratchet, and an operative connection between the box body and said pawl adapted to accommodate lateral movement of the box body with respect to the pawl.

3. In a journal box, a box body, a pedestal operatively supporting the box body, an adjustable wedge interposed between the box body and the pedestal, a wedge bolt rotatable for adjusting the wedge, a ratchet for rotating said bolt, a slide block, a pawl carried by the block to coact with said ratchet, and an operative connection between the box body and said block for shifting the block incident to forward and rear movement of the box body.

4. In a journal box, a box body, a pedestal operatively supporting the box body including a pedestal brace, an adjustable wedge interposed between the box body and the pedestal, a wedge bolt rotatable for adjusting the wedge, a ratchet for rotating said bolt, a housing mounted on the pedestal brace, a block slidably in said housing, a pawl carried by the block to coact with the ratchet, and an operative connection between the box body and said block for shifting the block incident to forward and rear play of the box body.

5. In a journal box, a box body, a pedestal operatively supporting the box body including a pedestal brace, an adjustable wedge interposed between the box body and the pedestal, a wedge bolt rotatable for adjusting the wedge, a ratchet for rotating said bolt, a housing mounted on the pedestal brace, a block slidably in said housing, a

pawl carried by the block to coact with the ratchet, an operative connection between the box body and said block for shifting the block incident to forward and rear play of 5 the box body, and a spring bearing between the pawl and housing pressing the pawl into engagement with the ratchet.

6. In a journal box, a box body, a pedestal 10 operatively supporting the box body, an adjustable wedge interposed between the box body and the pedestal, a wedge bolt rotatable for adjusting the wedge, a ratchet for rotating said bolt, a slide block, a pawl carried by the block to coact with the ratchet, 15 a yoke carried by the box body, and a cross rod forming a connection between said yoke and block for shifting the block incident to forward and rear movement of the box body.

7. In a journal box, a box body, a pedestal 20 operatively supporting the box body, an adjustable wedge interposed between the box body and the pedestal, a wedge bolt rotatable for adjusting the wedge, a ratchet for rotating said bolt, a slide block, a pawl carried 25 by the block to coact with the ratchet, a yoke carried by the box body, and a cross rod forming a connection between said yoke and said block for shifting the block incident to forward and rear movement of the box 30 body, said rod being slidable upon the block

whereby the rod may shift laterally with respect to the block with the yoke and box body.

8. In a journal box, a box body, a pedestal 35 operatively supporting the box body, an adjustable wedge interposed between the box body and the pedestal, a wedge bolt rotatable for adjusting the wedge, a ratchet for rotating said bolt, a slide block, a pawl carried by the block to coact with the ratchet, 40 a yoke carried by the box body, and a cross rod forming a connection between said yoke and said block for shifting the block incident to forward and rear movement of the box body, the yoke being provided with slots 45 freely receiving said rod whereby the yoke may shift vertically with respect to said block with the box body.

9. In a journal box, a box body, a pedestal 50 operatively supporting the box body including a pedestal brace, a wedge interposed between the box body and the pedestal and adjustable for taking up forward and rear play of the box body, and a right and left threaded wedge bolt carried by the pedestal 55 brace and operatively engaged with the wedge for adjusting the wedge.

In testimony whereof I affix my signature

EDWARD W. RAWDON. [L.S.]
